A. STREULI

PROTECTOR

Filed Sept. 25, 1925

334 Alfred Streuli ^{inventor}

Hardway & Gathay
Attorneys

UNITED STATES PATENT OFFICE.

ALFRED STREULL, OF GALVESTON, TEXAS.

PROTECTOR.

Application filed September 25, 1925. Serial No. 58,523.

This invention relates to protectors and more particularly to that class of protectors used to protect the face, eyes and neck of persons having their hair shampooed.

Persons having their heads shampooed, or having their heads washed have difficulty in keeping the water and suds from getting in their eyes, mouth and ears and down their neck, and one object of the invention is to provide a device of the character described that will overcome this difficulty.

Another object of the invention is to provide a device of the character described which will be light, inexpensive and comfortable to the wearer and which may be made to fit the heads of various persons.

With the above and other objects in view the invention has particular relation to certain novel features of construction, operation and arrangement of parts which is described and claimed in this specification and illustrated in the accompanying drawings, wherein:

Figure 1 is a plan view, partly in section, of the device.

Figure 2 is a sectional view taken on the line *a*—*a* of Figure 1, and

Figure 3 shows the device as applied to the head while in use.

Referring now more particularly to the drawings, wherein like numerals of reference designate similar features in each of the figures, the numeral 1 refers to the protector as a whole, which is preferably made of rubber, the numeral 2 refers to the brim which is of convenient width, usually

about the width of a hat brim, which is somewhat thickened at the edges as shown at 3.

A head band 4 is provided to fit snugly around the head of the wearer near the hair line and is made elastic so as to fit more than one sized head and to keep water, and soap suds from getting in the eyes or on the face and neck of the wearer when he is getting a shampoo or getting his head washed. This band is relatively thick at its base and tapers to a thin upper edge as shown in Figure 2 of the drawings and when pulled down upon the head of the wearer, being elastic, fits the head tightly and prevents the soapy or other water from getting to the face of the wearer.

This device may be stiffened as much as desired by insertion of stiffeners 5, or in any other suitable manner, that will keep the brim 2 stiff enough to stand out from the head of the wearer.

A device of this character is cheaply manufactured and very useful for the purpose for which it is intended.

What I claim is:

A protector comprising a substantially annular flexible brim having a central opening to receive the head of the wearer, said opening being surrounded by an elastic head band to which the brim is secured, said band having a relatively thick base and tapering to a thin upper edge.

In testimony whereof I have signed my name to this specification.

ALFRED STREULL,
